UNITED STATES PATENT OFFICE

105,603

DESIGN FOR A DRESS ENSEMBLE

Margaret Michelson, New York, N. Y.

Application June 28, 1937, Serial No. 70,088

Term of patent 3½ years

To all whom it may concern:

Be it known that I, Margaret Michelson, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

The characteristic feature of my design resides in the jacket member of the ensemble, which jacket consists of a short body section ornamented by Shirring within the all-over stitched blocks and plain collar and cuffs, as shown.

I claim:

The ornamental design for a dress ensemble, substantially as shown and described.

MARGARET MICHELSON.
